UNITED STATES PATENT OFFICE.

CHARLES K. STINSON, OF BOSTON, MASSACHUSETTS, ASSIGNOR TO THE
COLBY WRINGER COMPANY, OF MONTPELIER, VERMONT.

CLOTHES-WRINGER.

SPECIFICATION forming part of Letters Patent No. 434,303, dated August 12, 1890.

Application filed December 10, 1889. Serial No. 333,236. (No model.)

To all whom it may concern:

Be it known that I, CHARLES K. STINSON, a citizen of the United States, residing at Boston, in the county of Suffolk and State of Massachusetts, have invented certain new and useful Improvements in Clothes-Wringers; and I do hereby declare the following to be a full, clear, and exact description of the invention, such as will enable others skilled in the art to 5
10 which it appertains to make and use the same.

My present invention relates to an improvement in clothes-wringers, the object of the invention being to improve the construction and operation of machinery of this class and provide a simple, cheap, and durable wringer for 15
20 domestic and laundry use; and the invention consists in the construction, arrangement, and combination of parts, substantially as will be hereinafter described and fully claimed.

25 In the accompanying drawings, illustrating the invention, Figure 1 is an end view of my improved clothes-wringer. Fig. 2 is a vertical sectional inner end view on the line $x x$ of Fig. 3. Fig. 3 is a side elevation in partial section. Fig. 4 is a detail perspective view of one of the cam-provided ends of the clothes-board casting. Fig. 5 is a perspective view of one of the roller-supporting jaws. Fig. 6 represents a side view and an edge view of 30
35 the parts shown in Fig. 4. Fig. 7 is a detail plan view of the clothes-board.

Like letters of reference designate like parts in all the figures.

This wringer has the usual pair of squeeze- 40
35 rollers, A denoting the upper roller, having journals $a a$, and B denoting the lower roller, having journals $b b$, said rollers being of suitable and convenient length and diameter, as well as material, such as gutta-percha, rubber, or other substance.

The main frame of my improved wringer consists, essentially, of two upright end castings C C, suitably shaped and formed to permit the arrangement therewith of the several 45
50 mechanical elements comprising the machine. The journals $a a$ of the upper roller A are located in bearings $c c$, situated within the lower ends of the vertically-elongated boxes, niches, or casings C' C', formed integral with and as 55
60 a part of the end castings C C, within which

boxes are the rubber springs $d d$, that rest upon the bearings $c c$ of the roller-journals, and are regulated by the set-screws $e e$, that pass through the top of the boxes or niches C' C', and also through the ends of the connecting-bar or arch D, which assists in keeping the ends of the main frame in place. The journal-bearings $c c$ are each provided on the outer side with an upwardly-projecting pin, spindle, or extension c' , which passes through 55
60 an opening in the connecting-bar D near its end. (See Figs. 1 and 3.) These lateral pins lie alongside of the rubber springs and enter the connecting-bar loosely. They serve to better unite the parts of the wringer together, 65 and thus make it stronger. They help to keep the rubber springs in place and are found useful in perfecting the arrangement of the upper portion of the wringer.

My present wringer, as is customary with 70
75 machines of this class, is intended to be clamped or secured to the tub or other receptacle with which it is used by means of suitable jaws. The outer jaws E E—that is, the jaws adapted to be on the outside of the tub—75
80 are cast integral with the end portions C C of the frame, and hence are rigid and stationary. The inner jaws F F are movably hung, and they support the lower roller B. One of these jaws is shown in perspective in Fig. 5. 80
85 The leg or jaw proper F has a tail or extension F', which is substantially at right angles to the part F, so that the casting of the said jaw may be said, irrespective of its particular contour, to be of a general right-angled form. Its vertex is provided with an integral journal-box f, projecting horizontally on each side of the main casting of the jaw and long enough to provide a sufficient bearing for the journal b belonging to the lower roller B. 90
95 Said journal-boxes f f project through slots in the end castings C C, as shown, which serve to keep the journals, and consequently the jaws, in place. The end of the tail portion F' is provided with a slot or elongated opening g, of any desired size and shape, to receive the crescent-shaped cam I on the ends of the clothes-board casting and likewise to permit the passage therethrough of the tie-rod on which these inner roller-supporting jaws 100

are pivotally mounted. By referring to Fig. 3 the inner jaws will be seen situated in their regular places adjacent to the inner faces of the end pieces C C, and the lower roller B 5 may likewise be observed with its journals b located respectively in the bearings f f of these movable jaw-castings.

The clothes-board is located between the castings C C and is a flat shelf or board G, 10 provided with an encircling casting, which surrounds one horizontal side and the ends thereof, said casting being a grooved rim K, adapted to receive the edges of board G. The extreme ends of the rim K are preferably 15 enlarged to a greater or less degree in a circular or other convenient shape h, thus presenting a vertical side or plate-like portion. Each of said enlarged ends of the clothes-board casting is perforated with a circular 20 opening i, (see Figs. 4 and 6,) and through these circular openings passes the horizontal tie-rod H, which also runs through the openings g g in the tails of the inner jaws, and, furthermore, has its ends projected through 25 the castings C C, wherein the rod is supported and which it serves to tie together, the said projecting ends of the tie-rod being furnished with nuts that are screwed up tightly against the outside faces of castings C C, as shown 30 in Fig. 1. The said enlarged ends of the clothes-board casting, in addition to being perforated, are provided with cams I I, preferably so placed as to be vertically above the perforations when the clothes-board is in its 35 horizontal, or substantially horizontal, position. These cams project horizontally from the parts h h. They have what may be termed a "crescent" shape, one side being concave and the other convex. The concave side is 40 coincident with the periphery of the adjacent perforation, while the convex side is preferably bulged or elliptically convexed, so as to make the cam of sufficient eccentricity to do its work. These crescent-shaped cams lie 45 within the slots g g of the movable inner jaws and operate against the edges of said slots. It will be noticed that the combination of tie-rod and cam forms the pivot or support on which each inner jaw is movably mounted.

50 Projecting horizontally from each of the inner jaws F is a pin l. These pins project toward each other. A connecting-tube J receives at one end one of the pins l and at the other end the other of said pins. (See Fig. 3.)

55 This tube will be arranged in place at the same time when the other wringer elements are being assembled.

The operation of my present invention will be obvious from the foregoing description of 60 the construction. The shelf or table G is adapted to be grasped and swung upward toward the upper roller, (see dotted lines in Fig. 2,) and also to be reversely moved into a horizontal position, or an approximately 65 horizontal position, as seen in Fig. 1. Upon lifting this clothes-board the inner jaws will readily open or recede from the fixed jaws,

so as to release the machine from a tub. By depressing the board the crescent-shaped cams are caused to act on the right-angled portions of the movable jaws, and as the tie-rod forms an unyielding pivot for the said board, this movement of the cams will exert a lifting force upon the tail ends of the jaws, which, together with the meeting of the rollers, will press the jaws toward the tub, thus gripping all the jaws tightly upon the tub, and simultaneously with this movement the lower rollers will be pressed upward against the other roller, for obviously when the movement of the jaw is obstructed by the tub, against which it comes in contact, the continued lifting pressure of the cams will force the lower roller upward, said roller being journaled in these movable jaws, and hence 85 it is understood that when the clothes-board is depressed this one movement thereof presses the rollers tightly together, and also grips or clamps the machine.

The contour, design, outline, and attachments of the jaws, levers, and other parts may be varied considerably without departing from my invention, and I therefore reserve the liberty to reconstruct and modify the mechanical elements of the invention 95 without departing from the spirit of the same.

Having thus described my invention, what I claim as new, and desire to secure by Letters Patent, is—

1. In a clothes-wringer, the combination of stationary outer jaws, squeeze-rollers, a suitably-supported clothes-board having cams at each end, movable inner jaws held upon a suitable support and provided with journal-bearings and slotted extensions, within which slotted extensions the cams operate.

2. In a clothes-wringer, the combination of stationary outer jaws, upper and lower squeeze-rollers, a cam-provided clothes-board, movable inner jaws provided with journal-bearings and slotted extensions, and a tie device supporting the clothes-board and having its opposite ends held by the outer castings.

3. The combination of the end castings having stationary jaws, the upper roller carried thereby, the inner movable jaws having slotted right-angled arms and horizontal journal-boxes, the lower roller having its journals in the said jaw-boxes, the clothes-board with its casting having enlarged ends perforated and provided with crescent-shaped cams, and the tie-rod running through said perforations and the slotted jaw-arms and held by the end castings, substantially as and for the purpose specified.

In testimony whereof I affix my signature in presence of two witnesses.

CHARLES K. STINSON.
